(57) **CLAIM**

The ornamental design for a fuel tank vent valve assembly, as shown and described.

DESCRIPTION

FIG. 1 is a top plan view of a fuel tank vent valve assembly in accordance with our new design;

FIG. 2 is a bottom plan view thereof;

FIG. 3 is a rear elevational view thereof;

FIG. 4 is a front elevational view thereof;

FIG. 5 is a side view thereof;

FIG. 6 is a top perspective view thereof; and,

FIG. 7 is a bottom perspective view thereof.

The broken line showing portions of the fuel tank vent valve assembly form no part of the claimed design.
